UNITED STATES PATENT OFFICE.

HARRY L. TANNER, OF BROOKLYN, NEW YORK, ASSIGNOR TO THE SPERRY GYROSCOPE COMPANY, OF BROOKLYN, NEW YORK, A CORPORATION OF NEW YORK.

GYROSCOPIC COMPASS.

Application filed June 28, 1916. Serial No. 108,380.

This invention relates to gyroscopic direction indicating instruments, and more especially to the type of such apparatus which has a positive directive power, that is an instrument which will seek the meridian, if displaced therefrom.

The principal object of the invention is to improve upon and simplify the type of gyrocompass disclosed in my patent for improvements in gyroscopic compasses, Patent No. 1,309,591, dated July 8, 1919.

Referring to the drawings in which what I now consider to be the preferred forms of my invention are shown: Fig. 1 is an elevation partly in section of a complete compass unit. Figs. 2 and 3 are a plan and vertical section, respectively, of the supporting stem for one of the torsion wires. Figs. 4 and 5 are a front and side elevation, respectively, of the damping spring and adjacent parts. Fig. 6 is an elevation showing a modified form of coupling between the gyroscopes. Fig. 7 is an end view of the same. Figs. 8 and 9 are enlarged details of the preferred form of coupling shown in Fig. 1. Fig. 10 is a top plan view showing a modified method of damping. Fig. 11 is an elevation of a modified form of compass. Fig. 12 is a similar view of another modification. Fig. 13 is a section on line 13—13 Fig. 11. Fig. 14 is a diagram showing the method of controlling the motor by the reversing contacts. Fig. 15 is a wiring diagram of the modified arrangement applicable to Fig. 12. Figs. 16 and 17 are diagrams illustrating the theory of operation.

The compass is shown as mounted in a bowl shaped stand which is provided with a removable cover 2, having a glass top 3. The stand is supported on a standard 4 from which ribs 5 extend to support the ring 6. The shell 7 of the bowl is made removable so that it can be lowered to inspect the compass. The outer gimbal ring 8 within which the inner ring 9 is pivotally supported on pivots 8' is shown as suspended from ring 6 by means of springs 11. The spider 10 is in turn pivoted to ring 9 by pivots 9' at right angles to pivots 8'. In Fig. 1, two of the pivots 8' and 9' are shown opposite each other to show their construction, but of course they are really placed at right angles to one another. The spider 10 is provided with a central elongated bearing member 12 which serves to pivotally support the azimuth movable unit 30

about the vertical axis. For this purpose the compass unit is provided with a vertical stem 13 journalled within bearing member 12 in antifriction suspension bearings 14 and 15. The rotatable unit 30 is provided with an extension 16 which may surround member 12 and is provided with collector rings 17 adapted to lead current into the rotatable unit from brushes 18 fixed to the spider 10. These rings not only bring in the three-phase current for driving the rotors, but also introduce current for the auxiliary control devices, hereinafter described.

The compass card is shown at 19 and is shown as supported from the rotatable unit by means of brackets 20, which also may serve to support the larger gear 21. A motor 22 fixed to the spider 10 is adapted to drive said gear through double reduction gearing 23 and 24. Said gear may also serve to rotate a transmitter 25 by means of which the readings of the compass are transferred to repeater compasses located at various parts of the ship, as will be readily understood by those skilled in the art. The rotatable unit is also preferably provided with a cam ring 26 which cooperates with mechanism (not shown) to introduce corrections in the reading of the compass for variations in the ship's speed, heading and latitude, by shifting the position of the rubber ring 27.

The gyroscopic units proper are mounted upon said rotatable unit for freedom about their vertical axes, and also for oscillation about horizontal axes within the support. As illustrating one form of such mounting I have shown the gyroscopes as mounted within vertical rings or precession members 28 and 29, which are pivotally supported about their vertical axes within the main frame 30. Preferably the vertical rings are suspended by means of torsion wires from the frame, as the wires not only serve to furnish a frictionless support, but also serve to centralize the vertical rings within the frame and to damp the oscillations of the compass about the meridian. The preferred construction for this suspension is shown in Figs. 2 and 3. A hollow stem 31 is supported from the top of frame 30 and has mounted within it a plurality of interfitting rotatable parts. The innermost part comprises a threaded thimble 32 having a restricted passage 33 adapted to clamp the head of the torsion wires 34. Said thimble is threaded in a ro-

- tatable sleeve 35, journalled within a second rotatable member 36. A set screw 37 is provided to lock member 36 to sleeve 31 when desired and a second set screw 38 supplied 5 to lock sleeve 35 to member 36. This construction furnishes not only a long torsion wire for supporting the vertical ring, but also provides means for adjusting both the torsion or twist of the wire and its length.
- 10 To adjust the length of the wire and thereby take more or less weight off the lower bearing 100 in the rotatable frame 30, the screw 38 is released while screw 37 is clamped down, and sleeve 35 is turned by means of a screw 15 driver. To adjust the torsion of the wire, screw 38 is tightened while screw 37 is released so that all the inner members are turned together. This last adjustment furnishes a valuable means for shifting the position 20 at which the gyroscope is centralized for different latitudes. A compass of this character, it is found, will not settle exactly on the meridian in north and south latitudes. The most convenient way of correcting this 25 defect is to apply a slight torque about the individual vertical axes of the gyroscopes through one or both of the torsion wires as described which will cause the gyroscopes to precess at the required rate to stay on the 30 meridian.

The rotor casings 40, 41, are pivoted on horizontal axes 42, 43 within their respective vertical rings 28 and 29. Preferably the pivots are placed above the center of gravity 35 of the casings and their contained parts, so that the rotors are pendulously mounted, although as will be evident to those skilled in the art, other systems of mounting may be adopted. Preferably also the rotors 101 40 within the casings are adapted to be normally driven in opposite directions one of said gyroscopes being, therefore, in an unstable condition. In Fig. 1 the spinning axes of rotors are at 102, 103 and are perpendicular to the 45 plane of the paper. The stator of rotor 101 is shown at 104.

A coupling means is provided for causing the main support to follow the orientation of the two gyroscopes and for other purposes 50 hereinafter described. Preferably this means is not directly connected to the support but extends between either the two vertical rings or the rotor casings. In the preferred form 55 of the invention this coupling extends between the rotor casings, and is shown as a pair of angular brackets 45, 46, one of which extends from each casing. One of the brackets is provided adjacent its end with a ball 47, which engages in a slot in the form of 60 a fork 48 in the lower end of bracket 46. By this means a simple but effective universal coupling between the casings is provided. This coupling, it will be seen, simply maintains a point attached to each casing in the 65 same relative position allowing all move-

ments of both the rotor casings and the vertical rings, which do not disturb this relation. Thus the casings may swing out about their horizontal axes in the same direction and may turn about the vertical axes of the rings in 70 opposite directions, but the casings cannot be turned about their horizontal axes in the opposite direction nor about the vertical axes in the same direction unless a compensating movement takes place about the other axes. 75 That is, the two casings may rotate in opposite directions about the horizontal axes if the vertical rings are also displaced, by remaining parallel to their original positions while the main support is rotated (see Fig. 80 17).

A system of contacts is arranged to operate the motor 22, above referred to. Preferably these contacts are mounted so as to be moved by rotation of the vertical rings in 85 opposite directions. They are shown as a pair of reversing contacts 50 mounted on a bracket 51, secured to vertical ring 28 and a cooperating brush or trolley 52 mounted on bracket 53 on ring 29. If the vertical ring 29 for instance should become displaced within the follow-up frame 30 the trolley rolls to one side or the other side of contacts and causes current to flow through one or the other of the field windings 122, 123 of the motor 22, thereby applying a torque about the vertical axis of the main support in the proper direction. The contacts are also completed by displacement of the rings under the special conditions above described. I find it advantageous to design the contact 50, 52 so that the main support will be continuously oscillated through a small angle by the rapid reversing of motor 22. For this purpose the air gap 150 between the two contacts is made 95 small so that the trolley 52 will touch both contact strips in the central position.

For damping the oscillations of the compass about the meridian, the torque of the suspension wires 34 proves very effective, but for damping the individual oscillations of the gyroscopes within the frame, I prefer to provide additional means. In Figs. 1, 4 and 5 this means consists of a spring 55 which is secured adjacent one end to a bracket 56 extending downwardly from the rotor casing 40, and adjacent its other end is secured to a fixed part 57 on the frame 30. It will be seen that the spring will be unaffected by rotation of the gyroscope about the vertical axis, but will be placed under tension by tilting about the horizontal axis within the frame and will in this position exert a torque about the vertical axes in opposite directions, the torque on one gyro being transferred to the other through the coupling 47. It will be obvious to those skilled in the art that other arrangement of the spring may be adopted within the scope of the appended claims to accomplish a similar result. Thus, instead of connecting

the spring at one end to frame 29, it will be obvious that it may be connected to any other point of the frame such as a point on the other gyro frame 41 corresponding to the point of connection to the gyro frame 40. Such construction is broadly suggested in Figs. 10 and 11.

Figs. 6 and 7 show a modified form of universal coupling for the gyroscopes. According to this form bracket 45' is provided with a pin 60 and on bracket 46' block 61 is journalled upon a vertical axis and provided with a central hole or slot 62 in which pin 60 loosely fits. It will readily be seen that this connection accomplishes substantially the same results as the ball and socket joint shown in Figs. 1, 8 and 9.

A modified form of damper for this type of compass is shown in Figs. 6 and 10. According to this modification a bracket 65 extends from ring 28, while a second bracket 66 extends from ring 29, the two brackets being connected by a tension spring 67, or other yielding means. Upon displacement of the rings, the spring exerts a torque about the horizontal axis of each gyroscope in opposite directions, through the universal coupling.

Referring now to Fig. 11 in which a substantial modification is shown, it will at once be seen that the main changes in the construction are the substitution of gears 70, 71 attached to the vertical rings 28' and 29' for the universal coupling attached to the gyro rotor casings. These gears furnish a ready means for permitting only equal and opposite rotation of the vertical rings about their pivotal axes. According to this modification also, the contacts which control the motor 22' are mounted upon the gyro rotor casings by means of brackets 72 and 73. Preferably the contacts are so arranged that they will actuate the motor 22' not only upon oscillation in opposite directions of the rotor frames about their horizontal axes, but also upon opposite rotation about their vertical axes. One method of accomplishing this result is to place the contacts to one side of the central or midway position between the two vertical rings, that is, out of line vertically with the line of contact between gears 70 and 71. By this arrangement of the contacts the motor is made to perform, in addition to the function it performs in the main form of the invention, some of the functions performed by the universal coupling between the rotor casings. As explained above with reference to Fig. 1, any tendency of the two gyroscopes to rotate in opposite directions about their horizontal axes will exert a torque about their vertical axes through said coupling. In Fig. 11 it will be seen that the gears 70 and 71 do not perform this function, but that upon such rotation about their horizontal axes, contacts 50' and 52' will be completed to actuate motor 22' and thus exert the desired torque about

the vertical axis of the frame. The idea of having a torque applied through motor 22 upon opposite rotation about their vertical axes is also made use of in this modification by positioning the contacts eccentrically as explained.

As pointed out above, the contacts 50' and 52' perform a double function. In Fig. 12 a modification is shown in which a set of contacts is employed for each function, that is, a pair of contacts 80, 81 are secured to the rotor casings and are actuated upon relative rotation of the gyro casings about their horizontal axes and a second pair of contacts 82, 83 secured to the vertical rings 28'', 29'' actuate the motor on relative displacement about their vertical axes.

The preferred form of damping means for this form of compass consists of a tension spring 90, which extends between brackets 91, 92 secured to the vertical rings 28' and 29' respectively. Adjacent its center the spring is secured to, or passes through, a downwardly extending arm 93 of a bell crank lever 94 (see Fig. 13). Adjacent each end of the lever is pivoted a piston 95 which works in a dashpot 96 secured to frame 30. It will be seen that upon relative rotation of the rings about their vertical axes the spring 90 will be moved laterally, and thus will push or pull upon the dashpots. Another effective damping means for this type of compass consists in employing very heavy, thick oil in the bearings 100 of the vertical rings (Figs. 1 and 12), these bearings preferably being of the ball bearing type.

The operation of my invention is, in general, as follows:—Let us suppose that the compass is off the meridian. The two gyroscopes will then begin to rise as the earth turns out from under them. As both casings are pendulums, this will result in a torque being applied about the horizontal axis of each gyroscope, and, as they are rotating in opposite directions, opposite precession will occur about their individual vertical axes. In other words, the vertical rings will move from the full to the dotted line position in Fig. 16. The showing in these figures is diagrammatic, only, as the movements that take place are greatly exaggerated for the sake of clearness. The main support 30 is shown merely as a rectangular base to illustrate its movements. From Fig. 16 it will be seen that by the said precessional movement, contacts 50, 52 will be completed, since trolley 52 has been moved to one side of point 150, thereby causing motor 22 to apply a torque about the vertical axis of the main frame 30 in the direction of the arrow. This will tend to cause opposite precession of the two gyros about their horizontal axes, causing one gyroscope to approach the vertical position and the other to become still further inclined. With the rotors running as indicated, rotor 41 in frame 130

29 would become further inclined. But, as explained above, this movement, acting through the universal coupling, will also displace the vertical rings by moving them 5 parallel to themselves and rotating the main frame (Fig. 17) by which the trolley is again brought to the neutral position 150. In addition it should be remembered that as soon as either vertical ring turns away from its 10 centralized position, the torsion suspension wire applies a torque about its vertical axes to cause precession about a horizontal axis. The result is that the elevation of gyro 41 is reduced and that of gyro 40 reversed, so that 15 the two gyros become equally and oppositely inclined about their horizontal axes. In this position, gravity acting on them will cause them to orient in the same direction, which acting through the coupling will, with the 20 assistance of motor 22, speedily bring the compass to the meridian, and the gyros to a position of equilibrium, after a few oscillations. As stated above, the oscillations about the meridian are quickly suppressed by 25 the damping effect of the torsion wires, while the pendulous oscillations of the gyros within the main frame are damped by the auxiliary yielding means 55, 67 or 90.

By comparing the operation of my invention 30 with that disclosed in my aforesaid application, it will be seen that I have been able to reduce the number of contacts employed and eliminate the torque applying means for exerting a torque opposed to that exerted by gravity about the horizontal axis of the unstable or oppositely rotating gyroscope by employing means which cause the said gyroscope to become inclined opposite to the normal inclination of a gyroscope, 35 when off the meridian, thereby enabling gravity to act upon the gyroscope in such a direction as to cause it to precess toward the meridian. Substantially the full directive force of both gyroscopes is again employed, 40 to bring the main support to the meridian. Also, all of the other advantages of this design of compass over the present types are retained, such as the elimination of deviations due to rolling and pitching of the ship 45 and deviations due to friction about the vertical axis of support.

In accordance with the provisions of the patent statutes, I have herein described the principle of operation of my invention, together with the apparatus, which I now consider to represent the best embodiment thereof, but I desire to have it understood that the apparatus shown is only illustrative and that the invention can be carried out by other 55 means. Also, while it is designed to use the various features and elements in the combination and relations described, some of these 60 may be altered, and others omitted without interfering with the more general results outlined, and the invention extends to such use.

Having described my invention, what I claim and desire to secure by Letters Patent is:—

1. The combination with a frame mounted for rotation about a vertical axis, a plurality of interconnected gyroscopes mounted thereon for rotation about vertical axes within the frame, and means responsive to relative movement about their individual vertical axes for exerting a torque about the axis of 75 said frame.

2. The combination with a frame mounted for rotation about a vertical axis, a plurality of interconnected gyroscopes mounted thereon for rotation about vertical axes within the 80 frame and for oscillation about horizontal axes, and means responsive to relative movement about their individual vertical axes for exerting a torque about the axis of said frame.

3. The combination with a frame mounted for rotation about a vertical axis, a plurality of gyroscopes mounted thereon for rotation about vertical axes within the frame and for oscillation about horizontal axes, a coupling 90 for preventing relative movement of the gyroscopes at a predetermined point, and means responsive to another relative movement of the gyroscopes for exerting a torque about the axis of said frame.

4. In gyroscopic apparatus, a supporting frame, a pair of precession members mounted thereon, a rotor and rotor bearing frame mounted for oscillation in each member, and a universal coupling connecting said bearing frames.

5. In gyroscopic apparatus, a supporting frame, a pair of precession members mounted thereon, a rotor and rotor bearing frame mounted for oscillation in each member, and a coupling connecting said bearing frames which prevents rotation of the members in the same direction and oscillation of the bearing frames in opposite directions.

6. A gyro-compass including a frame 110 mounted for movement about a vertical axis, a gyroscope, means mounting said gyroscope in the normally centralized position in said frame for turning about a vertical axis within the frame, said gyroscope normally rotating in a counter clockwise direction, looking north, and means brought into action by the turning of the gyroscope and mounting means within the frame about said vertical axis away from its centralized position for 115 applying a torque about the vertical axis of the frame.

7. A gyro-compass including a frame mounted for movement about a vertical axis, a gyroscope, means mounting the same for turning about a vertical axis and oscillation about a horizontal axis within the frame, said gyroscope normally rotating in a counter clockwise direction, looking north, contact means brought into action by the turning of 120

the gyroscope within the frame away from the meridian and a motor controlled by said contact for applying a torque about the vertical axis of the frame in such a direction as to cause the elevation about the horizontal axis to be reduced or reversed.

8. In a gyro-compass, a main support, a gyroscope and means for suspending the gyroscope from said support comprising a post on said support, a plurality of interfitting sleeves revolvably supported therein, a wire suspended from one of said sleeves and connected to the gyroscope, the suspension sleeve being threaded into the adjacent sleeve, releasable means for locking said adjacent sleeve to an outer sleeve, means for preventing relative rotation of said suspension sleeve and said outer sleeve and releasable means for locking the outer sleeve to the post.

9. In gyroscopic apparatus, a main support, a pair of rings mounted thereon for movement about parallel axes, a rotor and rotor bearing frame mounted within each frame for oscillation about an axis at an angle to said parallel axes, and a coupling means for maintaining both the rings and the frames in a predetermined relation comprising a slotted arm secured to one bearing frame and a ball secured to the other bearing frame and normally positioned in said slot.

10. In a gyroscopic compass, a support mounted for orientation, a pair of gyroscopes adapted to be oppositely rotated, mounted thereon for turning about vertical axes and oscillation about horizontal axes within said support, and means including a universal coupling connecting said gyroscopes brought into action by the turning of the gyroscopes in opposite directions about their vertical axes for causing the natural elevation of one of the gyroscopes to be reduced or reversed.

11. In gyroscopic apparatus, a main support, a pair of rings mounted thereon for movement about parallel axes, a rotor and rotor bearing frame mounted within each ring for oscillation about an axis at an angle to said parallel axes, and resilient damping means connected to a bearing frame which applies a torque about the said parallel axes of the gyroscopes upon tilting of said frame about said second mentioned axis.

12. The combination with a frame mounted for rotation about a vertical axis, a plurality of gyroscopes, means mounting said gyroscopes in said frame for rotation about vertical axes within the frame and for oscillation about horizontal axes, and universal coupling means interconnecting said gyroscopes.

13. The combination with a frame mounted for rotation about a vertical axis, a plurality of gyroscopes, means mounting said gyroscopes in said frames for rotation about vertical axes within the frame and for oscillation about horizontal axes, universal coupling means interconnecting said gyroscopes and resilient means connected to a gyroscope for applying a torque about its vertical axis upon inclination thereof within the frame.

14. A gyro-compass comprising in combination two gyroscopes, one in stable and one in unstable equilibrium, and viscous damping means acting about the vertical axes of the gyroscopes.

15. A gyro-compass comprising in combination a frame, a suspension therefor, two gyroscopes mounted in the frame, one of which is in stable equilibrium and the other in unstable equilibrium, the direction of rotation of the unstable gyroscope being opposite to that of the other and viscous damping means acting on an axis of the gyroscopes whereby their mutual reactions damp the oscillations of the compass and prevent deviation due to periodic lateral movement.

16. In a gyro-compass, the combination with a supporting frame mounted for orientation, a pair of gyroscopes mounted thereon for rotation about vertical axes and oscillation about horizontal axes within the frame, a coupling between said gyroscopes for exerting torques on each gyroscope about its horizontal axis on relative displacement of said frame and gyroscopes, means for displacing said frame, control means for said first named means responsive to said relative displacement of said frame and gyroscopes, said means being designed to cause frequent reversal of the torque applied by said first named means about said horizontal axes.

In testimony whereof I have affixed my signature.

HARRY L. TANNER.
